HUMIDIFIER

Filed March 28, 1930

FIG. 1

INVENTOR
ANDREW U. JONES

BY *Johnston Haugh & Co*
ATTORNEYS

UNITED STATES PATENT OFFICE

ANDREW U. JONES, OF MONTREAL, QUEBEC, CANADA

HUMIDIFIER

Application filed March 23, 1930. Serial No. 439,760.

This invention relates to humidifying apparatus in which steam is employed as a humidifying agent. More particularly, the invention is directed to an improved humidifier of the type comprising a steam diffusing pipe adapted to be connected to a source of live steam, such as the steam supply pipe leading to a radiator.

An object of the invention is to provide a humidifier including a steam diffusing pipe which is connected to the supply pipe of a radiator in such manner that the operation of the humidifier is controllable independently of the operation of the radiator.

Another object is to reduce steam condensation within the steam diffusing pipe by arranging said pipe to lie, throughout all or a major portion of its length, in close proximity to the live steam pipe to which it is connected.

A further object is to provide the steam diffusing pipe with steam discharge openings arranged opposite and close to the live steam pipe, so that the impingement of the escaping steam upon the heated surface of the live steam pipe further retards the formation of condensate.

A still further object is to provide novel means for causing evaporation of the condensate formed within the steam diffusing pipe.

Other purposes, advantages and characteristic features of the invention will be more readily understood from the following detailed description and accompanying drawings, wherein

Figure 1 is a perspective view of a radiator and live steam pipe assembly equipped with my invention.

Figure 2 is an enlarged fragmentary detailed view of the live steam supply pipe showing clearly the manner in which my invention is associated therewith.

Figure 3 is a view, principally in vertical section, of a slight modification.

Referring more particularly to the drawings, 11 designates a radiator equipped with a live steam supply pipe indicated at 12. Pipe 12 may be provided with any suitable form of valve 13 for controlling admission of

steam to the radiator 11. According to the present invention, I provide a valve casing 14 which is connected to the pipe 12 between the valve 13 and the source of steam. Valve casing 14 may be equipped with any suitable type of valve 15 for controlling the flow of steam from the pipe 12 to the steam diffusing pipe 16. Diffusing pipe 16 is formed to present a vertical portion 16a lying in close proximity to the live steam pipe 12 and an offset upper portion 16b connected to the bottom of the valve casing 14. The vertical portion 16a of the diffusing pipe 16 is formed with a plurality of relatively small openings 16c positioned close to and directly opposite the live steam pipe 12. At its lower end, the vertical portion 16a of the diffusing pipe is provided with a relatively small opening 16d for the escape of condensate.

When the valve 15 is opened, steam flows from the live steam supply pipe 12 through the valve casing 14 into the steam diffusing pipe 16. The steam escaping from the pipe 16 through the openings 16c impinges directly upon the adjacent heated surface of the live steam pipe 12, so that condensation is reduced to a minimum. Condensation of the steam within the diffusing pipe 16 is also retarded by the arrangement of this pipe to extend in close parallel relation with respect to the heated live steam supply pipe 12. The small amount of condensate forming within the diffusing pipe 16 flows downwardly through openings 16d onto a suitable absorbing material 17 which may consist of blotting paper wrapped around the live steam pipe 12 and held in place by suitable split clamps 17a of well-known construction. By reason of its contact with the pipe 12, the absorbent material 17 is maintained at a sufficiently high temperature to effect rapid evaporation of the condensate delivered thereto. The thickness of the absorbent material 17 should be relatively slight so that the entire body of the absorbent material may be maintained at a temperature sufficiently high to prevent any cooling of the condensate delivered thereto.

In Figure 3, I have shown a desirable modification, wherein the steam diffusing openings

19 are confined to the lower portion of the diffusing pipe 20 and are covered by the upper portion of the absorbent material 21 to which the condensate is delivered.

5 In the foregoing I have disclosed several ways in which the steam delivered to the steam diffusing pipe is permitted to escape into the atmosphere. It will be understood, however, that this feature of the invention 10 may be varied to provide for escape of the steam into the atmosphere in any suitable manner, although, in certain installations, it will be found preferable to have the escaping steam directed against the heated steam 15 supply pipe, as shown in Fig. 1, as this materially reduces condensing of the escaping steam. In both forms of the invention, as herein disclosed, it will be noted that the condensate formed within the steam diffusing 20 pipe is delivered to a highly heated body of absorbent material so that rapid evaporation of the condensate is provided for in such manner as to avoid objectionable drippage. This delivery of the condensate to an absorbent body of material heated by the live 25 steam pipe is a very important feature of the invention. It provides for rapid evaporation of the condensate and practically eliminates drippage.

30 I claim:

1. The combination with a vertically extending live steam pipe, of a vertically extending steam diffusing pipe having its upper end connected to said live steam pipe, said diffusing pipe being provided with a plurality of openings for the escape of steam and with a bottom opening for the escape of condensate, and a body of absorbent material surrounding the live steam pipe and positioned to receive the condensate formed within the diffusing pipe.

2. The combination with a live steam pipe of a diffuser connected thereto and functioning to diffuse steam into the atmosphere, said diffuser having an opening in the lower portion thereof for the escape of condensate and a body of absorbent material surrounding the live steam pipe and positioned to receive the condensate escaping through said opening.

3. The combination with a vertically extending live steam pipe of a vertically disposed diffuser connected thereto and functioning to diffuse steam into the atmosphere, said diffuser having an opening at its lower end for the escape of condensate and a body of absorbent material covering said opening and surrounding the live steam pipe, the arrangement being such that the absorbent material is heated by the live steam pipe so that the condensate absorbed by said material is evaporated into the atmosphere.

In witness whereof, I have hereunto set my hand.

ANDREW U. JONES.
